CARBURETOR

Wilfred F. Vallier, Fort Smith, Ark.

Application May 13, 1942, Serial No. 442,802

1 Claim. (261-47)

The present invention relates to new and useful improvements in carburetors, particularly for internal combustion engines, and has for its primary object to provide, in a device of this character of the type comprising a float chamber, novel means for removing the fuel vapors or fumes from said float chamber and mixing them with the ingoing charge, thus promoting fuel economy in addition to increasing the general efficiency of the engine.

Another important object of the invention is to provide an engine carburetor of the aforementioned character which comprises means for automatically shutting off the fumes or vapors when the throttle valve is closed.

Still another important object of the invention is to provide a carburetor of the character described comprising a construction and arrangement which is such that the fumes or vapors will be thoroughly broken up or atomized prior to their introduction into the charge.

Other objects of the invention are to provide a carburetor for engines which will be comparatively simple in construction, strong, durable, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a carburetor constructed in accordance with the present invention.

Figure 2 is a top plan view thereof.

Figure 3 is a view in vertical longitudinal section through the device, taken substantially on the line 3-3 of Figure 2.

Referring now to the drawings in detail, it will be seen that the embodiment of the invention which has been illustrated comprises a metallic body 1 which is adapted to be bolted at 2 to the intake manifold of an internal combustion engine. The body 1 is provided with a removable head 3. At an intermediate point, the body 1 is provided with a vertical, circular passage 4 which extends through the head 3.

One end portion of the body 1 is formed to provide a float chamber 5 for the reception of fuel. The level of the fuel in the chamber 5 is controlled by a needle valve 6 which, in turn, is actuated by a float 7.

The head 3 above the float chamber 5 has

formed therein an air chamber 8. The chamber 8 communicates with the atmosphere through ports 9. Mounted in the air chamber 8 is a substantially bell-shaped air spreader and baffle 10. The spreader 10 is spaced from the walls of the chamber 8. Further, the spreader 10 extends downwardly into the float chamber 5 to a point adjacent to but spaced from the level of the fuel therein.

10 Rising from the upper portion of the spreader 10 is a threaded neck 11 which projects through an opening 11' which is provided therefor in the top of the head 3. The upper portion of the spreader 10 is formed to provide a shoulder 12 for abutting engagement with the top of the chamber 8. A securing cap 13 is threaded on the neck 11. A screen 14 is provided for the ports 9. The screen 14 encircles the neck 11 and has its inner marginal portion secured between the cap 13 and the head 3. A suitable gasket 15 prevents leakage between the neck 11 and the cap 13.

15 The passage 4 extends through the head 3 and mounted in the upper portion thereof is a liner 16 which is secured in position by a set screw 17. 20 Mounted in the liner 16 is a spiral baffle 18. A vertical tube 19 is supported in the liner 16 by the spiral baffle 18.

25 Mounted in the passage 4 at an intermediate point is a fuel jet 20. The jet 20 includes an angular fitting 21 which communicates with the float chamber 5 for receiving fuel therefrom. The fitting 21 has mounted thereon beneath the tube 19 a substantially conical valve 23.

30 Operable in the passage 4, below the fuel jet 20, is a throttle valve 31 of the butterfly type. The shaft 32 of the throttle valve 31 has fixed thereon an arm 33 the purpose of which will be presently set forth. Any suitable means may be provided for actuating the throttle valve 31.

35 On the other end portion of the body 1 is a vaporizer and mixer 34. The device 34 includes a chamber 35 which communicates with the passage 4, at a point below the throttle valve 31, through a passage 36. A valve 37 controls the 40 passage 36. The shaft 38 of the valve 37 has fixed thereon an arm 39. A rod 40 connects the arm 39 to the arm 33. Thus, the valves 31 and 37 are connected for operation in unison.

The head 3 is provided with a comparatively small chamber 41 which communicates with the chamber 35. The lower portion of the wall of the chamber 41 is formed to provide a seat 42. Headedly mounted for adjustment in the lower end portion of the atomizer 34 is a plug 43 having a vertical socket 44 therein. A socket 45

in the head 3 is in vertical alignment with the socket 44. The sockets 44 and 45 slidably receive the end portions of a stem 46. Fixed on the stem 46 at an intermediate point is a poppet valve 47 which is engagable with the seat 42 for controlling the communication between the chambers 41 and 35. A coil spring 48 encircles the lower portion of the stem 46 and has one end engaged with the plug 43 and its other end engaged beneath the valve 47 for yieldingly urging said valve toward closed position on the seat 42. The tension of the coil spring 48 may be regulated as desired by adjusting the threadedly mounted plug 43. A spring latch 49 releasably secures the plug 43 in adjusted position.

The intermediate portion of a substantially C-shaped pipe 50 extends through the cap 13. This pipe 50 has formed therein an opening 51 (see Fig. 3) which communicates with the interior of the cap 13 and the spreader 10. The pipe 50 terminates in inturned end portions 52 which communicate with the chamber 41 on diametrically opposite sides thereof.

It is thought that the operation of the device will be readily apparent from a consideration of the foregoing. Briefly, with the engine running, fuel from the float chamber 5 is drawn in the usual manner into the passage 4 through the jet 20. Air from the atmosphere is also drawn downwardly into the passage 4. The portion of the incoming air which passes through the tube 19 impinges upon the substantially conical valve 23 and is uniformly spread thereby and mixed with the fuel as it leaves the upper end of the fitting 21 beneath the valve 23. The rest of the incoming air from the atmosphere is caused to whirl rapidly about the jet 20 by the spiral baffle 18 and in this manner the fuel and air are thoroughly mixed. The valve 31 opens and closes with the throttle valve 31. With the valve 31 in open position the engine suction opens the valve 47 against the tension of the coil spring 48 and, through the medium of the pipe 50, the cap 13, the spreader 10, et cetera, air is drawn into the chamber 8 through the ports 9, said air passing through the screen 14. This air passes down under and then up into the substantially bell-shaped spreader 10, picking up the fuel vapors or fumes in the upper portion of the float

chamber 5. The fumes and air are drawn through the pipe 50, the chambers 41 and 45 and the passage 36 where they mix with the ingoing charge. As the fumes and air flow past the valve 47 from the chamber 41 and enter the comparatively large chamber 35, they expand and are further vaporized and mixed.

It is believed that the many advantages of a carburetor constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

A carburetor of the character described comprising a body having a main mixture passage 20 therein for communication with an engine manifold and the atmosphere, said body including a removable head, a float chamber for the reception of fuel in the body, means for discharging fuel from the float chamber into the passage, 25 the head having an air chamber therein communicating with the float chamber, said head further having air intake ports therein communicating with the air chamber and still further having an opening therein, a substantially bell-shaped spreader mounted in the air chamber in spaced relation to the walls thereof and extending downwardly therefrom into the float chamber, a neck on the spreader extending through the opening in the head, a screen on 30 the head over the ports, a cap threadedly mounted on the neck for securing the spreader in position, said cap being engaged with the screen, said cap communicating with the spreader, another chamber in the body, the third-named chamber communicating with the passage, a pipe extending through the cap and communicating therewith at an intermediate point, 35 said pipe communicating, at its ends, with the third-named chamber, a valve controlling the passage, a valve controlling the communication of the third-named chamber with said passage, and means connecting the valves for opening and closing the same in unison.

WILFRED F. VALLIER.
